(57) **CLAIM**

The ornamental design for a day lounger, as shown and described.

DESCRIPTION

FIG. 1 is a perspective view of a front side of the day lounger.

FIG. 2 is an elevational view of the front side thereof.

FIG. 3 is an elevational view of a rear side thereof.

FIG. 4 is top plan view thereof.

FIG. 5 is a bottom view thereof.

FIG. 6 is an elevational view of a first lateral side thereof.

FIG. 7 is an elevational view of a second lateral side thereof.

FIG. 8 is a perspective view of the front side thereof illustrating cushions, shown in broken lines.

FIG. 9 is a perspective view of a front side of a center section of the lounger.

FIG. 10 is a perspective view of a rear side of the center section of the lounger.

FIG. 11 is a perspective view of a front side of an end section of the lounger.

FIG. 12 is a perspective view of a rear side of the end section of the lounger.

FIG. 13 is a perspective view of a front side of a middle section of the lounger; and,

FIG. 14 is a perspective view of a rear side of the middle section of the lounger.

The broken line portions of the disclosure are for illustrative purposes only and form no part of the claimed design.

Individual components of the claimed day lounger are shown separately at FIGS. 9 through 14 for completeness of disclosure.
